UNITED STATES PATENT OFFICE.

WILLIAM L. MERSFELDER, OF DETROIT, MICHIGAN, ASSIGNOR TO DETROIT STOVE WORKS, OF DETROIT, MICHIGAN, A CORPORATION OF MICHIGAN.

FIRE-BOX LINING.

1,250,200.

Specification of Letters Patent. Patented Dec. 18, 1917.

Application filed April 6, 1917. Serial No. 160,135.

To all whom it may concern:

Be it known that I, WILLIAM L. MERSFELDER, a citizen of the United States of America, residing at Detroit, in the county 5 of Wayne and State of Michigan, have invented certain new and useful Improvements in Fire-Box Linings, of which the following is a specification, reference being had therein to the accompanying drawings.

10 The invention relates to cooking-stoves, ranges or other appliances, and more particularly that type in which the fire-box is arranged in front or at the side of the oven. It is the object of the invention to provide 15 means for preventing the overheating of the oven adjacent to the fire-box and at the same time to pre-heat the air which is introduced and distributed to the ignited coal within the fire-box so as to secure better and more 20 nearly smokeless combustion.

In the drawings:

Figure 1 is a cross-section through a portion of the stove to which my improvements are applied;

25 Fig. 2 is a front elevation of the liner-plate; and

Fig. 3 is a plan view.

A is the fire-box, and B is the oven of a cooking-stove or range of the usual type.

30 C is a liner-plate for the rear side of the fire-box adjacent to the oven B. This plate is provided with lugs D for separating the same from the oven wall and at the top with an overlapping flange E for engaging 35 the top F of the oven. The plate is also provided at a plurality of points with passages G opening to the rear at the top and beneath the flange E, and opening to the front at points H, thereby forming down-

40 turned air passages. The front of the plate C is also provided with a series of laterally-extending grooves I, each forming a succession of arcs described about points substantially midway between the points H and

45 either communicating with or approaching the passages G at the ends of said arcs. These grooves will distribute the air which passes from the back of the plate C through

the downturned passage G, and the cross-section of each groove is sufficiently small 50 to avoid obstruction by the lodgment of fuel therein.

With the construction as described in operation, the chimney draft will create sufficient difference in pressure to cause the 55 air from the ash-pit section to pass upward between the plate C and the oven wall and then downward through the passages G and distributing channels I. During this movement the heat imparted to the plate from 60 contact with the fuel will be partially absorbed by the air current, thereby avoiding overheating of the oven, and at the same time the air is raised in temperature, causing 65 a hot air blast. Thus when the air is finally commingled with the fuel gases smokeless combustion will be produced. The 70 advantageous feature of the construction is that the air passages will not become clogged either with fuel or ashes. This is 75 for the reason that the downturned passages G are protected by the front wall or baffle J, and, as before stated, the grooves are of a cross-section which will prevent lodgment of fuel therein. As a consequence a very 80 uniform distribution of the heated air is obtained, which will maintain uniform combustion.

What I claim as my invention is:—

In a stove, the combination with a fire- 80 box and oven section, of a liner for said fire-box spaced from the oven to form an air chamber and having a plurality of relatively small inclined air passages extending therethrough opening at their lower ends 85 into the fire-box and at their upper ends into said air chamber, the front face of said liner being formed with a series of grooves extending in downward curved arcs between points vertically aligned with said air passages and adapted to deflect air discharged 90 through said passages laterally along the surface of said plate.

In testimony whereof I affix my signature.

WILLIAM L. MERSFELDER.
